UNITED STATES PATENT OFFICE.

NATHAN HEYMANN, OF NEW ORLEANS, LOUISIANA.

RAT GUARD.

Application filed May 9, 1925, Serial No. 29,181. Renewed May 18, 1927.

My invention is a rat guard which is adapted to be secured in place on the mooring cable or hawser of a ship, to prevent rats from passing along the cable or hawser between the ship and a dock, and it consists in the combinations, constructions and arrangements herein described and claimed.

An object of the invention is the provision of a rat guard which can be secured releasably yet firmly to a cable of any one of a plurality of different sizes without there being any necessity of threading the cable through an opening in the guard.

A further object of the invention is the provision in a rat guard of a novel highly efficient means for releasably securing the rat guard in a desirable position on a cable of any one of a plurality of different sizes.

A still further object of the invention is the provision of a rat guard which can be applied to or removed from a cable quickly and easily, is not likely to get out of order easily or to be impaired by the weather or other causes in service, can be manufactured cheaply, and is thoroughly practical commercially.

Other objects and advantages of the invention will be apparent from the following description, considered in conjunction with the accompanying drawings, in which

Figure 1 is a perspective view showing the improved rat guard applied to a cable.

Figure 2 is a central vertical section through the guard,

Figure 3 is a face view of the sections of the body of the guard separated from each other,

Figure 4 is a perspective view of the binding ring which is comprised in the means that the invention provides for securing the body of the guard in place upon a cable.

The body of the improved guard is made up of two sections 1 and 2 respectively each of which preferably is a segment of a circle, the section 1 being substantially semi-circular in outline while the section 2 is slightly greater in area. With this arrangement, the radial edge portions of the section 2 will overlap the corresponding edge portions of the section 1, as indicated at 3 in Fig. 1 when the sections 1 and 2 are arranged so that the body which these sections form is circular in outline. The lapped portions of the two sections are detachably secured together by bolts 4 and nuts 5 or other suitable fastening devices.

The sections 1 and 2 preferably are made of galvanized sheet metal but may be of any other suitable material which is sufficiently strong and rigid for the purpose for which the device is intended and is not likely to be impaired or detrimentally affected by the weather.

The body of the guard has a central opening which is formed of two complementary notches or cut outs 6 and 7 in the sections 1 and 2 respectively. This central opening is circular and is of slightly greater diameter than the largest cable or hawser to which the device is likely to be applied in the service for which the device is intended.

The sections 1 and 2 are secured together by means of bolts 4 which extend through aligned openings in the lapped edge portions of the sections and nuts 5 so that a cable, such as indicated at 8 in Figure 1, to which the device is to be applied passes through the central opening 6-7 of the body of the guard. The body of the guard is releasably held in place on the cable and is stayed against swinging flatwise against the cable when the cable is taut by fastening means which comprises a circular series of spring arms 9 which extends laterally of one face of the body 1-2 in concentric relation to the central opening 6-7 of the body of the guard, the respective spring arms 9 having outwardly turned attaching portions 10 at their inner ends and each of the attaching portions 10 being secured rigidly by rivets 11 to one of the sections 1 or 2 adjacent to the cut out or notch 6 or 7, as the case may be, in that section so that the spring arms 9 will be arranged in a circular series concentric to the central opening 6-7, as stated, when the sections 1 and 2 are secured together as hereinbefore described.

The outer end portions of the spring arms 9 may be bent or rolled outwardly and rearwardly as indicated at 12 to provide stops for preventing a binding or constricting ring 13 from slipping or sliding outwardly on the spring fingers 9 beyond the outer ends of such spring fingers. The binding or constricting ring 13 is a split ring made of material possessing inherent resiliency and having outwardly turned cooperative lugs 14 as the meeting ends of the ring. The shank of a bolt 15 extends through aligned apertures in the lugs 14 and is threadededly engaged by a nut 16.

From the foregoing description of the

various parts of the device, the operation thereof may be readily understood. The body 1—2 of the guard is arranged on a cable 8 of a given size so that the cable 5 passes through the central opening of the body. The spring arms 9 then will extend laterally of the body of the guard alongside a portion of the cable and these spring fingers are forced inward and held in position to grip the cable by means of the binding ring 13 which can be adjusted through the agency of the bolt 15 and nut 16 to clamp the spring fingers or gripping members 9 against a cable of any one of a plurality 15 of different sizes. Since the spring fingers 9 engage with the cable for a considerable distance from the plane of the body 1—2 or at a considerable distance from the plane 20 of the body 1—2, it is manifest that the body of the guard not only will be held against movement longitudinally of the cable but also will be held against oscillating or swinging flatwise from a plane which intersects the cable at right angles when the cable 25 is taut. The guard therefore will be effective to prevent rats from passing along the cable between a ship and a dock when the ship is moored to the dock by means of the cable. Of course, the device can be secured 30 in place on any other cable to prevent rats or other small animals from passing along the cable between the places at which the opposite ends of the cable are secured.

Obviously, the invention is susceptible of 35 embodiment in forms other than that illustrated in the accompanying drawings, and I therefore consider as my own all such modifications and adaptations thereof as fairly fall within the scope of the appended claims.

I claim:—

1. A rat guard comprising a body consisting of two cooperative plate sections having lapped portions at their adjacent edges, means for releasably securing the lapped portions of the two sections together, said sections being cooperatively formed to provide a central opening in the body and at the adjacent edges of the sections when the sections are secured together, spring fingers secured to said sections in positions to form 50 a circular series concentric with said central opening, and an adjustable binding ring encircling said spring fingers, said spring fingers having stops at the outer ends thereof for preventing said binding rings from slipping from the outer ends of the spring fingers.

2. A rat guard comprising a body formed of two cooperative segmental plate sections having lapped adjacent edge portions, means for releasably securing said lapped edge portions together, said sections having complementary cutouts in their adjacent edges to form a central opening in the body when the lapped edge portions of the sections are 60 secured together, said central opening being adapted for the reception of a cable on which the body is to be secured, a series of spring fingers extending laterally of one side of the body in adjacent concentric relation to 65 said central opening, a split binding ring encircling said spring fingers, and means adjustably connecting the meeting portions of said split binding ring for adjusting the effective area of said binding ring to clamp 70 said spring fingers to a cable of any one of a plurality of different sizes.

NATHAN HEYMANN.
